The ornamental design for an airblast fuel nozzle, as shown and described.

DESCRIPTION

FIG. 1 is a top, front perspective view of the airblast fuel nozzle showing my new design;

FIG. 2 is a bottom, rear perspective view thereof; and, FIG. 3 is a top plan view thereof.

The broken line showing in the figures is for illustrating unclaimed portions of the airblast fuel nozzle and forms no part of the claimed design.

The claimed surfaces extend from the solid lines to the broken lines.
